Primary Examiner — Wendy L Arminio*(74) Attorney, Agent, or Firm* — Hall Estill Law Firm(57) **CLAIM**

The ornamental design for a bottle chug lid, as shown and described.

DESCRIPTION

FIG. 1 is a perspective view of my new design of a bottle chug lid.

FIG. 2 is a front side elevation view of FIG. 1.

FIG. 3 is a rear side elevation of view of FIG. 1.

FIG. 4 is a right side elevation view of FIG. 1.

FIG. 5 is left side elevation view of FIG. 1.

FIG. 6 is a top view of FIG. 1.

FIG. 7 is a bottom view of FIG. 1; and,

FIG. 8 is a perspective view of the bottle chug lid of FIG. 1, shown in a condition of use on an unclaimed bottle drawn in broken lines.

The broken lines in FIG. 8 illustrating a bottle depict environmental structure and form no part of the claimed design. All other broken lines depict portions of the bottle chug lid that form no part of the claimed design.
